UNITED STATES PATENT OFFICE.

HENRY WEBSTER, OF COVENTRY, ENGLAND.

KILNS FOR BURNING ANY AND ALL SORTS OF CLAY PRODUCTS, GLAZED WARE, AND POTTERY.

Application filed October 15, 1926, Serial No. 141,745, and in Great Britain October 17, 1925.

This invention relates to kilns for burning clay products either glazed or unglazed, and particularly relates to continuous burning of round and rectangular kilns; and it has for its object economy in fuel and labour and a more efficient heat treatment or burning of the clay products.

According to the present improvements, a plurality of kilns are so connected together by flues that the gases of combustion from any one kiln may be passed to any other kiln or kilns, or whereby any one kiln may be used independently of the others. In other words the kilns are so connected that the draught or flow of heat is under complete control from one kiln or kilns to any other kiln or kilns, and there may be either an up draught or a down draught in any of the kilns. Waste heat may be passed from any one kiln or kilns or all the kilns to a waste heat flue delivering to driers or for use for any other purpose. The kilns are conveniently of the round type and a flue may encircle the inside of the kiln so that the heat may pass up this flue and down the interior through the floor of the kiln to the underground portion of the kiln or the draught may be reversed to pass through the floor of the kiln over the bag wall and down into the surrounding flue.

In order that the invention may be clearly understood and readily carried into practical effect reference is made in further describing the same to the accompanying drawings, wherein,

Figure 1 represent, diagrammatically, two parallel series or batteries of kilns, constructed, inter-connected and arranged in accordance with this invention, the upper series being shown in ground floor section on the line 1—1 of Figure 2 and the lower series being shown in section below the ground level on the line 2—2 of Figure 2.

Figure 2 and 3 are vertical sectional and outside elevational views respectively of one of the kilns. These figures are drawn to a larger scale than Figure 1, Figure 2 being taken on the line 3—3 in Figure 1.

Figure 4 is a sectional view taken through two adjacent kilns and showing an alternative arrangement in which there are two flues for each kiln.

Figure 5 is a sectional view of a muffle

kiln taken at right angles to the longitudinal flues.

Referring to the general arrangement shown in Figure 1, the various kilns, for convenience of reference are numbered 1, 2, 3, 4, 5 etc. and although there are, as shown, six kilns in each series it is to be understood that there may be any desired number of kilns in each series and any desired number of series.

The series of kilns are preferably arranged, as shown, in parallel rows.

In the arrangement shown, the draught may pass from the transverse flue *a* into kiln No. 1, up the annular flue *b* and over the bag walls *c*, and down through the floor *d* of the kiln to the transverse flue *a*¹ on the other side of the kiln. Similar transverse flues *a*, *a*¹ are arranged at each side of the other kilns, the two flues between each kiln being connected at one side to a chimney or smoke stack *e*.

The kilns of each series are also capable of being directly connected with each other by a central longitudinal flue *f* passing across the transverse flues beneath the kilns. The other sides of the transverse flues *a*, *a*¹ run into a longitudinal flue *g* passing along the inside of each series of kilns. There are thus two longitudinal flues between the two series of kilns and a third longitudinal flue *h* may be provided between the flues *g* for receiving waste heat which can be passed to driers or for any other useful purpose.

All these flues are controlled by dampers *i* at the junctions so that the heat may be controlled to pass from any one kiln or kilns to any other kiln or kilns, or by means of these dampers the flues may be so controlled that there may be an up draught or a down draught in the kilns. In the same way the flues may be also so controlled that any one kiln may be used independently of any other kiln. For this purpose the walls of the flues at the junctions may either be constituted by sliding plates or built up of refractory bricks and cement which can be readily dismantled as and when it is required to alter the direction of the draught. By thus opening or closing any one of the four walls *i* of each or any junction the flue gases may be caused to take any desired direction.

In the lower part of Figure 1 the open and

closed walls of the junctions are shown by dotted and full lines respectively. Thus the kiln No. 1 may be cooling and the waste heat therefrom may be delivered, as shown by the 5 arrows, direct from this kiln to the waste heat flue passing to the dryers or utilized for any other purpose desired.

Kiln No. 2 may be cooling and the waste heat passed on to kiln No. 6 as shown for 10 drying and preliminary heating the clay products therein, the draught in this case being directed upwardly through the floor *d* of No. 6 and down into the annular flue *b* to the chimney *e* between kilns Nos. 5 and 6, 15 as indicated by the arrows.

Kiln No. 3 may be utilized for salt glazing or periodic burning, the draught in this case passing as shown, direct to the chimney between kilns Nos. 3 and 4.

20 Kiln No. 4 may be on full fire, the gases of combustion passing through the flue *f* directly connecting kilns Nos. 4 and 5 across the two transverse flues *a*, *a'* between them, the flue gases also passing up the annular flue *b* in kiln No. 5 and down through the floor *d*, thus preheating the ware in kiln 25 No. 5 before passing to the chimney between kilns Nos. 5 and 6, all as shown by the arrows.

30 The kilns at the ends of the two series of kilns are connected by a transverse flue *a'* which passes on the outside of the two kilns to convey the waste heat across from one series of kilns to the other. Thus providing 35 an endless circle of kilns with any number or all in use at the same time.

In an alternative arrangement, shown in 40 Figure 4, there are two flues *f'*, *f''* to each kiln. The flue *f'* runs direct from the annular flue *b* of one kiln to the annular flue *b* of the next adjacent kiln. The other flue *f''*, 45 which runs below the first along the whole length of the kilns, communicates with each of the kilns below the floor by means of a central draught hole *k*. By this arrangement the waste heat can be made to take any desired course by suitably manipulating the various dampers. For example, if the right 50 hand kiln in Figure 4 is on full fire the heat passes over the bag walls *c* and down through the perforated floor and draught hole *k* into the bottom flue *f''*. By closing the damper *i'* at the right hand side of this flue the heat passes towards the left hand.

55 This flow of heat may be diverted into any desired direction. It may, for instance, pass right along the bottom flue *f''* to the next kiln and pass up through the draught hole *k* and the perforated floor of the kiln, over the bag walls *c* and down into the annular flue *b*. Or, as shown, by closing the bottom flue *f''* between the kilns by means of the damper *i''* and operating either or both of the dampers *i'* and *i''* in the top flue *f'*, the heat 60 may pass into the annular flue *b* in the left

hand kiln, over the bag walls *c* and down through the perforated floor *d* of this kiln into the bottom flue *f''* by way of the draught hole *k*. Or, again, the heat may be diverted into either of the transverse flues *a*, *a'* by 70 closing the damper *i''* and opening the appropriate damper therefor, that is to say the waste heat can be directed to the chimney, the central waste heat flue, or to any other kiln either with an up draught or a down 75 draught as desired.

Precisely the same arrangement as shown in Figure 5, can be adopted for muffle kilns for burning terra cotta, enamelled ware, pottery and the like goods which must not come 80 into contact with the fire. In this case there may be either an up draught or a down draught. In the latter case the heat from the furnace passes into the division between the kiln wall and the muffle over the top of 85 the muffle *m* and down the vertical flue *n* to the underside of the floor *d* and thence into the bottom longitudinal flue *f''* whence it may pass to the chimney or to other kilns as desired. Or waste heat from other kilns may 90 enter by way of the top flue *f'* into the annular flue *b* over the top of the muffle and down the vertical flue *n* into the base of the kiln whence it may pass into the bottom kiln 95 and thence to the chimney or waste heat flue. Or again the waste heat may enter by the bottom flue *f''* and pass up the vertical flue *n* over the top of the muffle and down into the annular flue *b* and thence by way of the top flue *f'* to the next or any other kiln or 100 to the waste flue *h* as desired.

It is to be understood that the application of the invention is not confined to circular kilns but is equally applicable to kilns of rectangular or other shapes.

105 What I claim and desire to secure by Letters Patent of the United States is,

1. In a plurality of kilns in which the annular flue of each kiln is connected by a short flue with the annular flue of the next adjacent kiln, the combination with a central longitudinal flue common to all of the kilns of the series and in operative communication with the well of each kiln and with each of the short flues, of a second longitudinal flue running alongside and common to all the kilns of the series, and transverse flues passing between adjacent kilns and adapted to establish communication between the second longitudinal flue and the central longitudinal and short flues, operative communication between the several flues being controlled by dampers.

2. In a plurality of kilns arranged in parallel series and in which the annular flue of each kiln is connected by a short flue with the next adjacent kiln, the combination with a central longitudinal flue common to all the kilns of each series and in damper controlled communication with the well of 120

each kiln of each series and with each of the short flues of each series, of a second longitudinal flue running along one side of and common to all the kilns of each series, a 5 third longitudinal flue running between the two series of kilns, a series of chimneys arranged along the other side of each series of kilns, and transverse flues passing between

the adjacent kilns of each series and in damper controlled communication with the 10 short and central longitudinal flues and with the chimneys at one end and with the second and third longitudinal flues at the other end.

HENRY WEBSTER.
